UNITED STATES PATENT OFFICE

LOUIS STEIN, OF CHICAGO, ILLINOIS

DISPLAY BOOK

Application filed January 27, 1933. Serial No. 653,793.

The invention relates generally to loose-leaf binders and other books of the type commonly employed by sales persons in showing articles or illustrations displayed on the pages of the book.

The general object of the invention is to provide, in a book of this type, a simple and conveniently operable device in the nature of an easel against which the pages of the book may be supported in an upright position in order better to display the material applied thereto.

Another object is to provide a supporting device so constructed and arranged that when the book covers rest in open position upon a table or the like, the pages thereof may be supported so as to expose simultaneously two opposed surfaces, one in an inclined upright position above one cover and the other in a horizontal position above the other cover.

Still another object is to provide an easel-like supporting device especially adapted for loose-leaf binders.

Other objects and advantages will become apparent from the following description taken in connection with the accompanying drawing, in which:

Figure 1 is a perspective view of a book embodying the features of the invention and showing the book in an open position with the pages on display.

Fig. 2 is a fragmentary perspective view of the book in a closed position but with one cover thrown open.

While the invention may be embodied in a book of the permanently bound type, it is especially adapted for loose-leaf binders. Accordingly, in the drawing, a loose-leaf binder is shown of the type which comprises a pair of covers 10 constructed to provide a pair of narrow strips 11 hinged to the respective covers at their adjacent edges and arranged to clamp between them a set of leaves or display sheets 12. Free relative swinging movement of the sheets 11 is assured in this type of binder by providing hinging strips 13 at the anchored edges of the sheets.

In carrying out my invention I employ a supporting device or easel, indicated generally at 15, which device is movable from a

folded position occupying but a small space within the book when closed to a position providing a support for the leaves in an upright position. Generally stated, it comprises in the preferred embodiment a brace or strut member 16 hingedly mounted on a carrier member 17 secured to one of the end sheets of the book at the bound edge thereof and connected with the strut by a flexible strap 18; and the arrangement is such that when the covers are opened outwardly and rest flat upon a desk or table, the strut and carrier may be readily moved into a position on one of the covers such as to form an inclined support for the sheets.

The strut 16 and carrier 17 are made of relatively stiff sheet material such as fibre board suitably covered, and are hinged together along one edge as at 19. To fasten the carrier 17 in position, it is formed with a hinge portion or attaching strip 20 adapted for binding into the book as by being clamped with the leaves 12 between the strips 11.

It will be observed that in its operative position, the strut 16 rests against the adjacent open cover 10, forming an angle with the carrier, so that the sheets 11 will be held in a substantially upright position as shown in Fig. 1. In its inoperative or collapsed position, the easel may be folded to occupy a small space in the book. For this purpose, the strut 16 is made slightly narrower than the carrier 17 so that it may lie flat against the carrier, thus avoiding the clamping strip 11. The flexible strap 18 being of relatively thin flexible material occupies no appreciable space between the members and may be readily folded merely by moving the strut against the carrier.

The construction employed is advantageous because of its simplicity and because of the ease with which it may be manipulated. On the latter account books or binders embodying the invention are especially useful in sales work and the like, for by a simple and practically imperceptible operation, the easel may be placed in operative position. Furthermore, a distinct advantage is gained in that the arrangement employed renders it

possible to display two sheet surfaces simultaneously.

I claim as my invention:

1. In a loose-leaf binder having a pair of covers and leaves having hinged portions bound together between the covers, an easel positioned between one cover and the adjoining leaf, and comprising a carrier and a strut of relatively stiff material hinged together 10 along one edge, the carrier having its opposite edge bound between the covers with the leaves and the edge of the strut opposite the hinge being adapted when opened to rest against the adjacent cover, said strut being 15 slightly narrower than said carrier so that it may lie flat against the carrier when the book is closed.
2. In a loose-leaf binder having a pair of covers and leaves bound together along 20 one edge, an easel positioned between one cover and the adjoining leaf and comprising a carrier bound at one edge with the covers and leaves, and a strut on the carrier adapted to rest against the adjacent cover 25 when in operative position.
3. In a book of the character described having a pair of covers and a set of leaves bound together along one edge, an easel swingably secured to one of the end leaves 30 of the set at the bound edge thereof and adapted to rest on one of said covers to hold the leaves in a substantially upright position.
4. In a book of the character described 35 having a pair of covers and a set of leaves bound together along one edge, an easel swingably secured to one of the end leaves of the set and adapted to rest on one of said covers to hold the leaves in a substantially 40 upright position.
5. In a book of the character described having a pair of covers and leaves having hinged portions bound together between the covers, an easel adapted to support said leaves 45 in an upright position, said easel comprising a carrier member and a strut member hinged together along one edge, the opposite edge of one of said members being hinged to one of said covers at the hinged edge thereof, 50 and the free edge of the other of said members being adapted to rest against the last mentioned cover to hold the easel in operative position.
6. In a loose-leaf binder having a pair of 55 covers and leaves having hinged portions bound together by the covers, an easel positioned between one of the covers and the leaves, said easel comprising a carrier member and a strut member hinged together along 60 one edge so that they may lie flat against each other when the book is closed, and an attaching strip hinged to the edge of one of said members opposite the hinged edge and bound with the covers and leaves.
7. In a book of the character described 65

having a pair of covers and leaves bound together along one edge, an easel positioned between one of the covers and the leaves, said easel comprising a carrier member and a strut member hinged together, one of said members being bound in the book, and a relatively thin flexible strap secured at its ends to adjacent faces of the members and adapted to fold flatly between the members when the book is closed.

8. An easel adapted to be secured in a book to hold the leaves in a substantially upright position, comprising, in combination, a carrier member and a strut member hinged to each other along one edge, the edge of one of said members opposite the hinged edge being formed to be secured in the book similarly to the leaves.

9. An easel adapted to be secured in a book having hinged leaves comprising, in combination, a carrier member and a strut member hinged to each other along one edge, and an attaching strip hinged to the opposite edge of one of said members and formed for binding into the book similarly to the leaves.

10. An easel adapted to be secured in a loose-leaf binder to hold the leaves in a substantially upright position comprising, in combination, a carrier and a strut hinged to each other along one edge, the edge of said carrier opposite the hinged edge being formed for binding into the book similarly to the leaves, and said strut being narrower than said carrier to permit them to lie flat against each other when the book is closed.

11. An easel adapted to be secured in a loose-leaf binder to hold the leaves in a substantially upright position comprising, in combination, a carrier member and a strut member hinged to each other along one edge, the opposite edge of said carrier being formed to be secured in the book similarly to the leaves, and a strap secured at its ends to adjacent faces of said members at points spaced from the hinged edge, said strap being of relatively thin flexible material to fold flat between said members when the book is closed.

In testimony whereof, I have hereunto affixed my signature.

LOUIS STEIN.
